UNITED STATES PATENT OFFICE

FRIEDRICH KÖNECKE, OF HANOVER, GERMANY

OVERSHOE

Application filed July 22, 1929, Serial No. 380,142, and in Germany July 27, 1928.

This invention relates to an overshoe intended to be used by persons, the feet of which are subjected to being sprinkled with water, as is the case with the men washing cars or 5 rolling stock, also men operating grindstones, and the like. I am aware of the fact that such persons are wearing rubber shoes while carrying out their respective jobs.

Now, according to the present invention, 10 shoes for the purpose in view, i. e. protecting the feet of the persons concerned from being sprinkled with water, comprise a wooden sole and a leather body and upper, this latter having at its rear an opening, the size of 15 which is so limited that it is just possible to put on and to pull off the overshoe and to prevent at all events an entrance of water thereto. That opening may be closed by a tongue and by a strap or straps and buckles. 20 If these members are employed, the opening may extend from the upper edge of the overshoe down to the wooden sole.

It has been found to be advantageous to 25 provide the upper of the overshoe at the lower ends of the opening and laterally therefrom with reinforcing pieces, also of leather, so as to prevent the thus covered portions of the upper from rending or tearing owing to the action of the water if this continues to act for a comparatively long time.

The upper surface of the wooden sole may be flat or plane so that the boot or shoe proper of the wearer of the overshoe is reliably supported on said sole.

30 Overshoes of the improved kind as described in general in the preceding paragraphs, and in detail hereinafter, are distinguished by their durability and their cheap price; besides, the feet are kept warmer than in rubber overshoes in that the wooden sole can be thick and is a by far worse conductor of heat than rubber which is very important if the overshoes must be worn on a bottom wet with fresh cold water. Also the 35 leather body and the upper keep warmer

than a rubber body and the upper, and the wooden sole affords a more secure hold on the wet bottom than is the case with rubber. Another point worth mentioning is this that the leather boot or shoes on which the overshoes have been put need not be polished again when the overshoes have been pulled off, the fact being that the polish is not impaired by the inner surface of the leather overshoes, whereas with rubber overshoes the 55 inner shoes or boots, or shoes or boots proper, must be polished again, in that the rubber destroys the polish.

The invention is illustrated diagrammatically and by way of example on the accompanying drawing, on which

50 Figure 1 is a side-view of an overshoe designed according to this invention,

Figure 2 is a rear view thereof, and

55 Figure 3 shows a modification of the constructional form illustrated in Fig. 2.

On the drawing, *a* denotes the wooden sole and *b* the upper of the overshoe. At the rear of the upper is a vertical opening (Fig. 2) extending from the upper edge of the upper 70 down to the sole.

75 *c* is a strap with a buckle by which the overshoe can be firmly attached to the upper of the wearer, just above the ankles. In the modification Figure 3 the opening is closed by a tongue *d*, and two straps with buckles are provided in this case. The tongue is sewn to one of the rims of the upper at the opening, but it may, if desired, be made integral with the leather of the upper. If a tongue is employed, the opening may also be located at a side of the overshoe or even at its front. A tongue is, however, not an indispensably requisite. Overshoes without a tongue can be more easily put on and pulled off and are 80 cheaper. Especially if the opening is at the rear of the overshoe the tongue can be dispensed with, in that the water enters into the overshoe generally at the front of the same.

85 I claim:

50

60

65

70

75

80

85

90

An overshoe, comprising, in combination,
a wooden sole with a heel and a leather up-
per having at its rear a vertical opening, the
width of which is less than the transverse
5 diameter of the heel of the shoe; reinforcing
pieces provided right-hand and left-hand
from said opening at those places where the
upper is affixed to the sole, and means for
fastening the overshoe to the leg of the
10 wearer.

In testimony whereof I affix my signature.

FRIEDRICH KÖNECKE.
